(57) **CLAIM**

The ornamental design for an engine for a brushcutter, as shown and described.

DESCRIPTION

FIG. 1 is a front perspective view of an engine for a brushcutter in accordance with our new design;

FIG. 2 is a rear perspective view of the engine for a brushcutter in accordance with our new design;

FIG. 3 is a front elevational view of the engine for a brushcutter in accordance with our new design;

FIG. 4 is a rear elevational view of the engine for a brushcutter in accordance with our new design;

FIG. 5 is a top plan view of the engine for a brushcutter in accordance with our new design;

FIG. 6 is a bottom plan view of the engine for a brushcutter in accordance with our new design;

FIG. 7 is a right side elevational view of the engine for a brushcutter in accordance with our new design;

FIG. 8 is a left side elevational view of the engine for a brushcutter in accordance with our new design; and,

FIG. 9 is a front perspective view of the engine for a brushcutter in accordance with our new design illustrating a state in which a brushcutter attachment is attached to the engine.

The broken lines showing environment in FIGS. 1-9 represents unclaimed subject matter and forms no part of the claimed design.
